The ornamental design for a taillight for motor vehicle, as shown and described.

DESCRIPTION

FIG. 1 is a left perspective view of a taillight for motor vehicle;

FIG. 2 is an elevation view thereof from the left side;

FIG. 3 is an elevation view thereof from the right side; and,
FIG. 4 is a front elevation view thereof.

The broken line showing of the taillight for motor vehicle is for the purpose of illustrating portions of the taillight for motor vehicle and forms no part of the claimed design.
